US0D1094312S

(12) **United States Design Patent** (10) **Patent No.:** **US D1,094,312 S**
(45) **Date of Patent:** **** Sep. 23, 2025**

(54) **COMPUTER INTERFACE**

(71) Applicant: **Coda Systems Limited**, Halstead (GB)

(72) Inventors: **Howard Davis**, Essex (GB); **George Davis**, Essex (GB)

(**) Term: **15 Years**

(21) Appl. No.: **35/516,360**

(22) Filed: **Nov. 17, 2022**

(80) **Hague Agreement Data**

Int. Filing Date: **Nov. 17, 2022**

Int. Reg. No.: **DM/226744**

Int. Reg. Date: **Nov. 17, 2022**

Int. Reg. Pub. Date: **Feb. 24, 2023**

(30) **Foreign Application Priority Data**

May 18, 2022 (GB) 6208841

May 18, 2022 (GB) 6208843

(51) **LOC (15) Cl.** **13-03**

(52) **U.S. Cl.**

USPC **D13/146**

(58) **Field of Classification Search**

USPC D13/133, 146, 147, 149, 148; D14/300, D14/301, 308, 310, 311, 312, 313, 348, D14/349, 353, 354, 355, 356, 357, 363, D14/368, 369, 370, 432, 433, 434, 435, D14/436, 441, 442, 444, 445, 446, 498, D14/502, 504, 135, 164, 299

CPC H01R 11/30; H01R 13/15; H01R 13/62; H01R 13/6205; H01R 13/2421; H01R 13/6456; H01R 24/60; H01R 24/30;

H01R 24/28; H01R 2201/06; H01R 2201/12; G02B 6/3886

See application file for complete search history.

(57)

CLAIM

The ornamental design for a computer interface as shown and described.

DESCRIPTION

2. Computer interface

4. Computer interface

2.1: Perspective

2.2: Front

2.3: side view

2.4: Back

4.1: Perspective

(Continued)

4.2: Front**4.3:** side view**4.4:** Back

Design 2 shows a 7-pin computer interface assembly;
 Design 4 shows a 9-pin computer interface assembly;
 The broken lines in the reproductions depict portions of the
 computer interface that form no part of the claim.

1 Claim, 8 Drawing Sheets
